UNITED STATES PATENT OFFICE.

ELMER A. SPERRY, OF CLEVELAND, OHIO, ASSIGNOR TO MORGAN ELECTRIC MACHINE COMPANY, OF EAST CHICAGO, INDIANA, A CORPORATION OF WEST VIRGINIA.

RACK-RAIL.

SPECIFICATION forming part of Letters Patent No. 772,971, dated October 25, 1904.

Application filed March 31, 1904. Serial No. 200,889. (No model.)

To all whom it may concern:

Be it known that I, ELMER A. SPERRY, a citizen of the United States, residing at Cleveland, in the county of Cuyahoga and State of Ohio, have invented a new and useful Rack-Rail, of which the following is a specification.

This invention relates to rack-rails, and especially to rack-rails adapted to be employed as a traction-rack and also as an electric conductor.

The object of the invention is to provide a construction of combined rack-rail and conductor which is simple in construction and efficient in operation.

15 The invention consists, substantially, in the construction, combination, location, and arrangement of parts, all as will be more fully hereinafter set forth, as shown in the accompanying drawings, and finally pointed out in 20 the appended claims.

Referring to the accompanying drawings, and to the various views and reference-signs appearing thereon, Figure 1 is a view in side elevation, parts broken off, showing a rack-rail embodying the principles of my invention and a construction and arrangement of insulating-support therefor. Fig. 2 is a view in transverse section of the construction shown in Fig. 1. Fig. 3 is a view in transverse section through 30 a rack-rail constructed in accordance with the principles of my invention and showing the application thereto of one form of fish-plate or rail-joint. Fig. 4 is a view in transverse section, showing a modified arrangement of 35 insulating sheath or support for the rack-rail and the application thereto of fish-plates or rail-joints. Fig. 5 is a view in side elevation, parts broken off and parts in section, showing another modified form of insulating-support 40 for the rack-rail embraced within the spirit and scope of my invention. Fig. 6 is a view in transverse section on the line 6-6, Fig. 5.

The same part is designated by the same reference-sign wherever it occurs throughout 45 the several views.

In the construction of rack-rail systems wherein the rack performs the double func-

tion of a traction-rack and an electrical conductor it is important to provide means whereby the rack is efficiently insulated in order to 50 enable it to perform its function of a conductor, while at the same time it is necessary to so mount and arrange the same and the insulation thereof as not to interfere with the operation thereof as a traction-rack or the 55 engagement therewith of a traction gear or sprocket carried by the locomotive or car and driven in a well-known manner. It is also important to provide against the accumulation of dirt or the like upon the rack, which 60 might otherwise interfere with proper electrical connection or contact between the rack and traction-gear which engages with it or with the function of the rack as a conductor. It is also necessary to solidly anchor the rack 65 as well against strains which are longitudinal as those which are lateral. It is also desirable to so mount the rack as to prevent accidental contact therewith.

It is among the special purposes of my 70 present invention to provide a construction of traction-rack rail and insulating-support or rail-joint connection wherein these desirable objects are attained.

Referring to the accompanying drawings, 75 reference-sign A designates the traction-rack rail, preferably U-shaped in transverse section and when placed in position for use, with the flanges forming the sides thereof being depending or presented downwardly from the 80 flat web portion connecting such flanges. These flanges are indicated by reference-sign B, and through the connecting-web are formed slots or openings C to receive the teeth of the sprocket-gear. (Indicated in dotted lines at 85 D, Fig. 1.) These slots or openings C impart the rack characteristic, said openings or slots being separated a distance apart corresponding or in registering relation with respect to the teeth of the coöperating driving 90 or sprocket gear, leaving unconnected web portion E (see Fig. 5) between adjacent slots or openings to afford the desired strength and rigidity of the traction-rack and to receive

the strains exerted by the pulling effort of the traction-gear. The outer surfaces of the flanges B preferably lie in parallel planes, as clearly indicated in the drawings, (see Figs. 5 2, 3, 4, and 6,) while the inner surfaces of the flanges B are beveled or taper toward the connecting-web of the rack. By this construction it will be observed that the traction-rack is provided with flanking surfaces or faces, 10 forming means for affording a lateral bearing therefor to resist any lateral strain which may be imposed upon the rack when in use. It is obvious that the holes or openings C may be of any suitable or desirable contour.

15 It is obvious that many specifically different constructions may be devised for suitably insulating the rack constructed as above described and of protecting the same against accidental contact. As one form of means 20 for accomplishing this result, to which, however, my invention is not to be limited or restricted, I employ longitudinal stringers F of insulating material—such, for instance, as wood—between which the rack A is clamped, 25 the proximate surfaces or faces of the stringers F lying against the flat parallel flanking surfaces of the flange B of the rack, the stringers F being clamped against the flat outer surfaces of the flanges B in any suitable 30 or convenient manner—as, for instance, by means of the clamp-bolts G. (See Fig. 2.) Preferably the distance between the top and bottom surfaces of the stringers is greater than the length of the flanges B, so that the 35 rack will rest below the top surfaces of the stringers F, so as to render the rack inaccessible except to the sprocket-gear which coöperates therewith, which gear enters the space between the stringers F to a sufficient depth 40 to effect intermeshing relation with the rack. In the manner described not only is the rack efficiently insulated, but any lateral bearing-support is afforded the same through the bearings of the flanking faces against the juxtaposed surfaces of the stringers. It will also 45 be seen that the stringers, in effect, constitute an insulating-sheathing, affording efficient insulation for the rack, and in order to secure rigidity of structure as between the stringers 50 and rack the clamping-bolts G or other securing means by which the stringers F are clamped against the flanking faces of the rack may be arranged to pass through the flanges B of the rack.

55 The rack and its insulating-sheathing, as above described, may be supported in the road-bed in any suitable or convenient manner so long as such support affords an insulation for the rack. In Figs. 1, 2, and 4 I have 60 shown the conductor-rack and its insulating-sheathing as supported upon transverse wooden ties or sleepers H. If desired, however, the rack and its inclosing sheathing may be supported upon insulators (indicated at J, 65 Figs. 5 and 6) in a well-known manner and

spaced convenient distances apart, and, if desired, the rack A may rest directly upon its insulating-support, as shown in Fig. 2, and in turn serve as a support for the housing or sheathing, such housing or sheathing being 70 braced against lateral movement in any suitable or convenient manner—as, for instance, by means of the bracket or casting K.

Where the rack is made up of sections placed end to end, such sections are bolted or otherwise secured together. In order to secure the necessary continuity of the rack when thus made up of sections and to enable the rack to shift its sections, it is necessary that the means employed for connecting adjacent 75 ends of the rack-sections be also of such character as will not detract from the conductivity of the conductor, and hence it is desirable to provide means whereby efficient electrical contact is maintained between the abutting 80 ends of adjacent sections of the rack. To this end I employ fish-plates at the joints between the abutting ends of adjacent rack-sections of such construction and arrangement as to serve as connecting means for such 85 abutting ends without at the same time interfering with the electrical continuity of the rack. In Fig. 3 I have shown one form of fish-plate or joint connection comprising a block L, which is exteriorly tapering to conform to the inner bevel or inclined or supporting surfaces of the flanges B of the rack, said block fitting into the space between such 90 flanges and being securely bolted or otherwise secured, as indicated at M, to the abutting 95 ends of adjacent sections of the rack. Thus it will be seen that the beveled or inclined inner surfaces of the flanges B afford means for securing an efficient contact between the rail-sections and the fish-plate or connecting-block L where the latter is wedged up in between the tapering flanges of the rack, it being readily seen that any upward pressure placed upon the fish-plate or block L by 100 its securing-bolts M affords a comparatively 105 powerful clamping action thereof. I do not desire to be limited or restricted to this form of connector or fish-plate, as other forms accomplishing the same objects may equally well 110 answer the purpose. For instance, in Fig. 4 I have shown fish-plates N arranged to be received in recesses or seats formed in the juxtaposed sides or surfaces of the stringers F and bearing against the outer flat parallel 115 surfaces of the flanges B of the rack, being clamped thereagainst in any convenient manner—as, for instance, by means of the belts O. In this form embodying the principles of my invention the desired electrical continuity of the rack is secured through the intimate bearing contact of the fish-plates N against the comparatively wide flat exterior 120 surfaces of flanges B of the rack, said fish-plates being efficiently clamped thereagainst 125 and not only securing intimacy of electrical 130

contact between abutting ends of adjacent rack - sections, but also affording efficient means for clamping or securing such ends together to secure mechanical continuity of the 5 rack.

In Fig. 6 I have shown another form of fish-plate embodying the principles of my invention and wherein the fish-plate constitutes a support for the rack and its inclosing or insulating housing or sheathing. In this form of embodiment P designates a casting suitably mounted upon an insulator or otherwise insulated from the ground and provided with the arms Q, which are designed to be clamped 10 against the outer flat sides or surfaces of the rack-flanges, being clamped together or into efficient bearing contact against the outer surfaces of the flanges in any convenient manner—as, for instance, by means of the bolts 15 R—the arms Q being received within convenient recesses or seats formed in the juxtaposed surfaces of the stringers F. In this manner the fish - plates constitute supporting means by which the rack and its sheathing 20 are supported and insulated.

From the foregoing description it will be seen that the traction-rack is substantially U shape in cross-section, the connecting-web portion of the rack being flattened and the 30 perforations or openings being formed therethrough. A rack of this contour is, in effect, a channel-bar and can be readily rolled in the manufacture thereof into the desired shape, and the outer surfaces of the flanges of the 35 rack afford wide lateral bearing-surfaces therefor not only for strengthening and securing rigidity of the rack, but also affording means for effecting efficient electrical continuity between adjacent sections of the rack 40 whether the connecting fish-plates be applied on the outside thereof, as shown in Figs. 4 and 6; or upon the inside and, between the flanges, as shown in Fig. 3.

It is obvious that many other modifications 45 and changes in the details of construction and arrangement would readily occur to persons skilled in the art and still fall within the spirit and scope of my invention. I do not desire, therefore, to be limited or restricted to 50 the exact details shown and described; but,

Having now set forth the object and nature 55 of my invention and various constructions and arrangements embodying the principles thereof, what I claim as new and useful and of my own invention, and desire to secure by Letters Patent, is—

1. A combined conductor and traction-rack having a perforated web portion, and integral flanges at the edges of the web; said 60 flanges extending laterally with respect to the plane of the web, and an insulating-support for said rack.

2. A combined conductor and traction-rack having a perforated web portion, and flanges 65 formed at the edges of the web portion, said

flanges extending parallel with respect to each other and at an angle to the plane of the web, and an insulating-support for said rack.

3. A combined conductor and traction-rack having laterally-extending parallel flanges at 70 the edges thereof, and a connecting-web, said web having perforations or openings therethrough, and an insulating-sheathing forming a housing for such rack, as and for the purpose set forth.

4. A combined conductor and traction-rack having lateral flanges at the edges thereof, and a perforated connecting-web, the outer surfaces of said flanges being parallel, and an insulating-sheathing for the rack having bearing 80 against the outer parallel surfaces of said flanges, as and for the purpose set forth.

5. A combined conductor and traction-rack having lateral flanges at the edges thereof, and a perforated connecting-web, the outer surfaces of said flanges being parallel, an insulating-sheathing for the rack having bearing 85 against the outer parallel surfaces of said flanges, and means for clamping said insulating-sheathing against such surfaces, as and for the purpose set forth.

6. A combined conductor and traction-rack, made in sections, each section having laterally-extending flanges at the edges thereof, and a connecting-web, said web being perforated, in 95 combination with a conductor connection applied to the surface of said flanges to secure mechanical and electrical continuity between said sections, as and for the purpose set forth.

7. A combined conductor and traction-rack, made in sections, each section having laterally-extending flanges at the edges thereof, and a connecting-web, said web being perforated, in combination with a conductor connection applied to the surface of said flanges to secure 105 mechanical and electrical continuity between said sections, and an insulating sheathing or housing for said rack, as and for the purpose set forth.

8. A combined conductor and traction-rack, made in sections, each section having laterally-extending flanges at the edges thereof, and a connecting-web, said web being perforated, in combination with a conductor connection applied to the surface of said flanges to secure 110 mechanical and electrical continuity between said sections, and an insulating-support for the rack, as and for the purpose set forth.

9. A combined conductor and traction-rack, having lateral flanges forming flanking surfaces at the edges thereof, and a perforated connecting-web, said flanking flanges being tapering in cross-section, as and for the purpose set forth.

10. A combined conductor and traction-rack, having lateral flanges forming flanking surfaces at the edges thereof, and a perforated connecting-web, said flanking flanges being tapering on the inner surfaces thereof, as and for the purpose set forth.

11. A combined conductor and traction-rack, having lateral flanges forming flanking surfaces at the edges thereof, and a perforated connecting-web, said flanking flanges having 5 parallel exterior surfaces and tapering inner surfaces, as and for the purpose set forth.

12. A combined conductor and traction-rack, in combination with an insulating sheathing or housing therefor, said sheathing or 10 housing being supported by said rack, as and for the purpose set forth.

13. A combined conductor and traction-rack, made in sections arranged end to end, each section having interiorly-tapering flanges 15 at the edges thereof, and a perforated connecting-web, in combination with an exteriorly-tapering connector applied between said flanges to secure mechanical and electrical continuity of said rack, as and for the purpose 20 set forth.

14. A combined conductor and traction-rack, made in sections arranged end to end, each section having lateral flanges forming

flanking portions, and a perforated connecting-web, in combination with a connector applied to the rack between said flanges to secure mechanical and electrical continuity of the rack, as and for the purpose set forth. 25

15. A combined conductor and traction-rack, made in sections arranged end to end, 30 each section having lateral flanges forming flanking portions, and a connecting-web, in combination with insulating-stringers applied against the exterior surfaces of said flanking portions, and connectors applied between said flanking portions to secure mechanical and 35 electrical continuity of the rack, as and for the purpose set forth.

In witness whereof I have hereunto set my hand, this 28th day of March, 1904, in the presence of the subscribing witnesses. 40
